CLEMENT J. HOWELL AND LENNA B. ODSON, OF SPOKANE, WASHINGTON.

CURTAIN ROD.

1,405,416.

Specification of Letters Patent. Patented Feb. 7, 1922.

Application filed March 17, 1921. Serial No. 452,997.

To all whom it may concern:

Be it known that we, CLEMENT J. HOWELL and LENNA B. ODSON, citizens of the United States, residing at Spokane, in the county 5 of Spokane and State of Washington, have invented certain new and useful Improvements in Curtain Rods; and we do declare the following to be a full, clear, and exact description of the invention, such as will 10 enable others skilled in the art to which it appertains to make and use the same.

This invention relates to an improved curtain fixture or drapery supporting rod as it is sometimes known, and it has for its 15 principal object to provide a device of this class including an extensible rod, one part of which has pivotal connection with a bracket which is permanently connected to an immovable frame, and a second bracket 20 with which the other part of the rod has detachable connection, this second bracket being designed for connection to a door or window, whereby when the curtain is hung on the rod, it will be moved with the door 25 or window.

Another object of the invention is to provide a curtain rod or fixture which will serve effectively for supporting curtains employed on double swing windows known as 30 casement windows.

Another and very important object of the invention is to provide a simple and effective device of this class which will carry the curtain with the door or casement window, 35 thereby doing away with the usual wear and tear on the drapery when hung from a stationary rod secured on frame above.

A further object of the invention is to provide a fixture of this type which is such 40 that it will permit the curtain to be moved independent of the door or window without removing it from the rod, thus permitting easy access to be had to the window for cleaning or repairing it without soiling the 45 curtain.

Other objects and advantages of the invention will be apparent during the course of the following description.

In the drawings forming a part of this 50 specification and in which like numerals are employed to designate like parts throughout the same,

Figure 1 is an elevational view of a portion of a door and its frame, showing our 55 improved curtain rod and the manner in which it is connected with the door and

frame, the curtain and supporting rings being shown in dotted lines.

Figure 2 is an enlarged elevational view, 60 with parts broken away and shown in section to disclose the construction of the rod more clearly, the curtain and other parts being omitted for sake of clearness.

Figure 3 is a top plan view showing the 65 curtain, its mounting rings and hook in full lines.

Figures 4 and 5 are sections taken on the lines 4—4 and 5—5 respectively of Fig. 2.

Referring to the drawings, wherein the preferred embodiment of the invention is 70 clearly illustrated, it will be seen that the numeral 1 designates one of the brackets which is adapted to be permanently connected to the door frame or window frame, this bracket being provided with a laterally 75 extending shank 2 to the outer end of which a cylindrical rod 3 is pivotally connected as shown at 2^a, this rod extending at right angles to this shank when the device is in position for use. Rod 3 telescopes into a sleeve 80 4 which is apertured at one end and provided, if desired, with an ornamental head 5. A second bracket 6 is designed to be connected to the door or swinging window in the manner disclosed, this bracket being provided 85 with a shank 7 which extends first laterally outward and then upward, being reduced in diameter at its free end as at 7^a for passage through the adjacent aperture in the sleeve 4. The curtain C is slidably 90 mounted on the extensible parts 3 and 4. by rings or the like r. It is to be noted, that one of the fasteners 8 for the bracket 1 includes a vertically disposed eye which serves 95 to permit a hook H which the curtain carries, to be engaged therewith for anchoring the curtain and always retaining it in proper place, thus insuring neatness of appearance and preventing possible accidental displacement of the same whether the door 100 is open or closed.

From the foregoing description, it will be seen that as the swinging window or door is opened or closed, the drapery or curtain will be carried with it. Now, if it is desired 105 to clean the window or replace a broken pane of glass, the curtain and swinging rod can be swung entirely to one side and out of the way so that free access to the window may be had without soiling or touching the curtain. Thus, the curtain can remain permanently 110 in place on the rod and the necessity

of removing and replacing the same for various reasons as now done, is entirely overcome. Furthermore, it will be seen that we have devised an extremely simple and advantageous fixture for supporting and connecting curtains and other drapery on doors and the like, which permits the drapery or curtains to be removed and replaced whenever necessary or desired; the construction and arrangement of the same being such that the fixture can be installed by inexperienced persons. These and other advantages and features of the invention have, no doubt, become apparent.

15 Since probably the best results may be obtained with the construction and arrangement shown and described, this construction and arrangement is taken as the preferred embodiment of the invention. However, we wish it to be understood that various minor changes in the shape, size and arrangement of parts may be resorted to without departing from the spirit of the invention or the scope of the subjoined claim.

20 25 We claim:

The combination with a stationary frame and a horizontally swinging closure hing-

edly mounted thereon, of a bracket element carried by the frame adjacent the hinged side of the closure and above the plane of 30 the upper edge of the closure and having a frame-engaging base and an arm extending straight out from the base, a bracket element carried by said closure adjacent its free side and having a closure-engaging base and an 35 arm extending out from its base and having its free end portion bent upwardly and at its end reduced to provide a pin, and a rod of telescoping sections having one end pivotally connected with the bracket of the frame for 40 horizontal swinging movement and its second end portion provided with an opening receiving the pin at the free end of the bracket of the closure, the rod adjusting itself longitudinally through telescoping of 45 its sections as the closure is swung from a closed to an open position and remaining in a horizontal position and in the same plane during swinging movement.

In testimony whereof we have hereunto 50 set our hands.

CLEMENT J. HOWELL,
LENNA B. ODSON.
